UNITED STATES PATENT OFFICE.

ROBERT J. DOUGHERTY, OF CANTON, ILLINOIS.

RAILROAD-CROSSING SIGNAL.

Application filed August 24, 1923. Serial No. 659,040.

To all whom it may concern:

Be it known that I, ROBERT J. DOUGHERTY, citizen of the United States, residing at Canton, in the county of Fulton and State 5 of Illinois, have invented certain new and useful Improvements in Railroad-Crossing Signals, of which the following is a specification.

This invention relates to certain new and 10 useful improvements in railway crossing signals and the primary object of the invention is to provide a device of this kind which embraces the desired qualities of simplicity, durability and efficiency.

15 A further object of the invention is to provide a railway crossing signal of such a nature that the same may be operated from a railroad station with facility and ease, and wherein pivoted signal arms may be 20 provided at a plurality of road crossings and operated from a single station simultaneously.

Other objects will appear as the nature 25 of the invention is better understood and the same consists in the novel form, combination, and arrangement of parts herein-after more fully described, shown in the accompanying drawings, and claimed.

In the drawings, wherein like reference 30 characters indicate corresponding parts throughout the several views,

Figure 1 is a side elevational view showing 35 a railway station equipped with a crossing signal constructed in accordance with the present invention.

Figure 2 is an enlarged fragmentary detail view in side elevation, showing the lever for operating the signal arms and adjacent parts.

40 Figure 3 is an edge view of the device shown in Figure 2.

Figure 4 is an elevational view of one of the signal arms and adjacent parts.

Figure 5 is a sectional view taken on the 45 line 5—5 of Figure 4, and

Figure 6 is an edge elevational view of one of the guide pulleys employed.

Referring more in detail to the drawings, 5 indicates a railroad station or tower house 50 at one side of which is mounted a plurality of posts or uprights 6, certain of said posts being mounted at opposite sides of the crossing indicated at 7. The posts 6 thus extend along the railroad tracks and each of 55 the same carries a pair of superposed guides

at its upper end as at 8 and which guides are preferably of the form shown in Figure 6, wherein they are shown as pulleys mounted within a casing 9 bolted to the post and preventing disengagement of the 60 wire or cable 10 therefrom.

The cable 10 is attached to the periphery of a drum 11 that is mounted upon a stand 12 within the station 5 and one strand passes over the upper pulleys 8^a and guides 8 and 65 around a relatively large guide pulley 13 mounted on the post farthest from the station. The return strand or lower strand of the cable then passes over the lower guides 8 under the pulley 8^b back to the 70 drum 11.

Extending between and connecting the posts at opposite sides of each crossing is a support 14 that is preferably in the nature of a cable suitably placed under tension and 75 this cable passes through an opening in a pivot bolt 15 of the adjacent signal arm 16 as shown in figure 5, the bolt 15 having a jamb nut 21 threaded thereon for securing the bolt 15 against movement on said 80 cable 14. This signal arm may be of any desired form but is preferably of a red color and provided with the word "Stop" 85 as indicated at 17. The signal arm 16 has a relatively short upper end portion 18 that is attached as at 19 to the upper strand 90 of the cable or wire 10, and the longer lower arm of the signal is adapted to assume a vertical position when operative.

Rigid with the drum 11 is a hand lever 90 20 by means of which said drum may be rotated, and it will thus be seen that when the lever 20 is swung in one direction, a pull is exerted upon the upper strand of the cable or wire 10 for swinging the signal arm to a 95 vertical position so as to give a warning to persons attempting to cross the railroad tracks of the approach of a train. On the other hand when the lever 20 is swung in the opposite direction, the lower strand of the 100 cable or wire 10 is pulled in one direction for correspondingly moving the upper strand thereof to cause the signal arms to swing to a horizontal raised position for indicating that the crossing is clear, or that no 105 train is about to approach the crossing.

From the above description, it is apparent that I have provided a very simple, durable and efficient form of crossing signal capable of being readily operated by a station agent, 110

and wherein the signal arms are disposed in a conspicuous position when in danger position.

Minor changes may be made without departing from the spirit and scope of the invention as claimed.

What I claim as new is:

1. In combination with a series of posts arranged alongside of a railroad track and certain of which are disposed at opposite sides of a crossing, a station at one side of which said posts are positioned, a cable guide carried by the post furthest from the station, a cable passing around said guide and having parallel upper and lower strands extending parallel to the track adjacent the posts, guides for said strands carried by said posts, a horizontal support connecting the posts at opposite sides of the crossing, a signal arm pivoted between its ends to said support for vertical swinging movement and having its upper end attached to the upper strand of said cable, and means within the station for selectively operating to exert a pull upon either strand of said cable at will.
2. In combination with a series of posts arranged alongside a railroad track and certain of which are disposed at opposite sides of a crossing, a station at one side of which said posts are positioned, a cable guide carried by the post furthest from the station, a cable passing around said guide and having parallel upper and lower strands extending parallel to the track adjacent the posts, guides for said strands carried by said posts, a horizontal support connecting the posts at opposite sides of the crossing, a signal arm pivoted between its ends to said support for vertical swinging movement and having its upper end attached to the upper strand of said cable, and means within the station for selectively operating to exert a pull upon either strand of said cable at will.

selectively operating to exert a pull upon either strand of said cable at will, said horizontal support comprising a cable under tension and the pivots of said signal arm having an aperture through which said cable extends.

3. In combination with a series of posts arranged alongside of a railroad track and certain of which are disposed at opposite sides of a crossing, a station at one side of which said posts are positioned, a cable guide carried by the post furthest from the station, a cable passing around said guide and having parallel upper and lower strands extending parallel to the track adjacent the posts, guides for said strands carried by said posts, a horizontal support connecting the posts at opposite sides of the crossing, a single arm pivoted between its ends to said support for vertical swinging movement and having its upper end attached to the upper strand of said cable, and means within the station for selectively operating to exert a pull upon either strand of said cable at will, said last named means embodying a drum within the station mounted for rotation, and to which the strands of said cable are attached, and a hand lever rigid with said drum.

4. In a railway crossing signal, a signal arm normally occupying an operative vertical depending position and having signal indicia on the lower portion thereof, means for pivotally supporting said signal arm for vertical swinging movement transversely of and above the crossing, and means operable from a point remote from the crossing to swing said signal arm to or from operative position at will.

In testimony whereof I affix my signature.
ROBERT J. DOUGHERTY.
